VALVED PUMP PISTON ASSEMBLY

Ottmar A. Kehle, Van Nuys, Calif., assignor to
Adel Precision Products Corp., a corporation of
California

Application March 6, 1945, Serial No. 581,317

7 Claims. (Cl. 103—178)

1

This invention relates to pumps of the manually operable type as used in the hydraulic systems of aircraft, and more particularly pertains to a valved piston assembly for such pumps and for such other uses and applications to which said assembly is suited.

One of the objects of this invention is to provide a valved piston assembly in which the piston rod, piston proper or piston head and certain novel check valve parts are constructed, combined and inter-related in such manner as to greatly reduce the amount of machining operations, the production costs, the amount of material employed, the servicing and upkeep costs and the number of parts compared to valved piston units as heretofore made.

Another object of this invention is to provide a valved piston unit such as described which may be quickly and easily assembled and disassembled.

A further object is to provide a valve piston assembly such as described wherein the piston rod and piston head are separate units, constructed and joined in a particular manner to assure the proper alignment and action thereof as well as to jointly accommodate a discharge check valve assembly which latter is of simple form by reason of the construction and arrangement of the rod and piston head.

Yet another object is to provide a valved piston assembly in which a single pin holds the piston rod and piston as well as the check valve assembly therein, in properly assembled relation subject to ready disassembly and replacement of parts of the entire unit.

With the foregoing objects in view, together with such other objects and advantages as may subsequently appear, the invention resides in the parts and in the combination, construction and arrangement of parts hereinafter described and claimed, and illustrated by way of example in the accompanying drawing, in which:

Fig. 1 is a fragmentary side elevation of a pump in which the present invention is embodied;

Fig. 2 is a fragmentary longitudinal sectional view of the pump showing the action of the valved piston during one stroke thereof;

Fig. 3 is a view similar to Fig. 2 showing the action of the valved piston during the opposite stroke;

Fig. 4 is a cross sectional view taken on the line 4—4 of Fig. 2.

As shown in the accompanying drawing, my improved valved piston is embodied in a pump which includes a cylinder 5 having an intake

2

port 7 controlled by an intake check valve 8 and a discharge port 9.

A suitable stuffing box 10 closes the end of the cylinder opposite the end closed by the construction of the cylinder for accommodating the check valve 8.

Slidable through the stuffing box 10 into the cylinder 6, is a piston rod 11 which is subject to reciprocation as by means of a lever 12 fulcrumed at 13 on a bracket 14 carried by the cylinder, there being a link 15 connecting the lever with said rod.

In accordance with my invention a piston or piston head 16 as a separate part is secured to the piston rod 11 by means of a pin 17 passed through aligned openings 18 and 19 in the piston and rod respectively, there being the usual sealing ring groove 20 in the piston and sealing ring 21 in said groove to prevent leakage between the cylinder wall and piston.

As here shown the piston has an axial bore 22 one end of which is reduced and opens through the outer end of the piston as an intake port 23, the reduction forming interiorly of the bore 22 a valve seat 24 for a ball check valve 25 freely movable in said bore. The other end of the bore 22 is counterbored to form a socket 26 for the squared end of the piston rod, this counterboring forming a shoulder 27 adapted to be abutted by the end of said rod. Opening into this counterbore are opposed radial discharge ports 28 which are adapted to register with corresponding opposed radial ports 29 in the socketed end of the piston rod 11, the ports 26 and 29 being spaced approximately 90° from the pin-receiving openings 18 and 19 in the piston and rod respectively. As here shown the ports 29 are spaced somewhat inwardly of the squared end of the rod and the ports 28 are correspondingly spaced from the plane of shoulder 27, thus providing imperforate socketed portions of the rod and piston at the shoulder 27 to assure stability and proper alignment of the piston and rod.

Formed in the socketed end of the piston rod 45 so as to register with the bore 22 in the piston head, as a continuation of said bore, is an axial bore 30 affording communication of the bore 22 with the registering ports 28 and 29. In this connection it is seen that the inner or skirt end 50 portion 31 of the piston through which portion the ports 28 extend, is exteriorly cut away, desirably in such a manner as to reduce its diameter to provide an annular space between it and the cylinder whereby fluid may flow freely through 55 the ports 28, thus completing a by-pass passage-

way which includes the port 23, bores 22 and 30 and ports 28 and 29. This passageway is comparatively large and direct and affords a large volume flow per stroke of the piston.

The ball check valve 25 is urged against its seat 24 by means of a spring 32 one end of which forms a socket for the ball while the other end seats on a U-shaped keeper member 33 which straddles pin 17 and seats thereon when the unit hereof is assembled as shown in Fig. 2. In straddling the pin 17 the U-shaped member 33 is held against displacement as an effective seat and assembly link for the spring and valve unit as a whole. By this arrangement the pin 17 holds the piston rod and the valve unit in assembled relation.

The inner end of the bore 30 in the piston rod is formed with a conical depression 34 against which the legs of the U-shaped member will seat when initially engaged in the bore 30 in assembling the unit. When the openings 18 and 19 are in registration and the pin 17 is inserted therein, the ends of the pin are sufficiently tapered to cause the pin to slide past the bight portion of the U-shaped member between the legs thereof so that the member will seat on the pin as shown in Fig. 2 with the legs slightly spaced from contact with the conical depression 34. This arrangement makes for an easy assembly of the unit and assures the holding of the member 33, spring 32 and ball valve in properly assembled relation.

It should be noted that the discharge check valve assembly is contained in part in the bore 22 in the piston and in the piston and in part in the bore 30 in the socketed end of the piston rod and that said assembly is shaped and dimensioned so as not to objectionably obstruct the flow through the by-pass passageway when the ball valve is unseated. The socketing of the rod in the piston as here provided and the manner in which the valve is mounted in the registering bores of the rod and piston make for a small, compact assembly subject to easy assembling and disassembling.

On the forward stroke of the piston assembly the check valve 25 is unseated by fluid pressure while the intake check valve 8 is forced against its seat, and fluid will pass freely through port 23, bores 22 and 30 and registering ports 28 and 29 thus by-passing the piston and passing out through the discharge port 9.

On the opposite or intake stroke of the piston the pressure of the fluid between the discharge port 9 and discharge valve 25 closes the latter while the suction action opens intake valve 8 thus allowing fluid to be drawn into the cylinder 6.

It will be apparent that I have provided a novel valved piston assembly which will attain the object hereof in a particularly efficacious manner by reason of the construction, relative arrangement and cooperation of the separate piston rod and piston head elements and the manner in which the discharge valve is combined therewith.

While I have shown and described a specific embodiment of my invention, I do not limit myself to the exact details of construction set forth, and the invention embraces such changes, modifications and equivalents of the parts and their formation and arrangement as come within the purview of the appended claims.

I claim:

1. In a structure of the character described, a piston cylinder, a piston head having a bore

extending axially therethrough, said bore being reduced at one end to define a valve seat interiorly of the bore, the other end of said bore being enlarged to define a piston-rod receiving-socket and a stop shoulder, one end portion of said head being of smaller diameter than the remainder of said head and adapted to define a space between said end portion and the cylinder in which the head is operated, a discharge port extending from the exterior of said reduced end portion and opening into said enlarged portion of said bore, a piston rod having an end portion mounted in said socket and abutting said shoulder, said end portion of said rod having an axial bore registering with the bore in said head and being formed with a discharge port affording communication of said registering bores with the discharge port in said head, a spring loaded check valve assembly mounted on said bores and normally seating on said valve seat, and a fastening pin inserted through said head and rod for holding them together.

2. In a structure of the character described, a piston cylinder, a piston head having a bore extending axially therethrough, said bore being reduced at one end to define a valve seat interiorly of the bore, the other end of said bore being enlarged to define a piston rod receiving-socket and a stop shoulder, one end portion of said head being of smaller diameter than the remainder of said head and adapted to define a space between said end portion and the cylinder in which the head is operated, a discharge port extending from the exterior of said reduced end portion and opening into said enlarged portion of said bore, a piston rod having an end portion mounted in said socket and abutting said shoulder, said end portion of said rod having an axial bore registering with the bore in said head and being formed with a discharge port affording communication of said registering bores with the discharge port in said head, a spring loaded check valve assembly mounted on said bores and normally seating on said valve seat, and a fastening pin inserted through said head and rod for holding them together, said check valve assembly including a valve member, a spring abutting said valve at one end, and a U-shaped spring seat abutting the other end of said spring and straddling said pin within the bore in said rod.

3. In a structure of the character described, a piston cylinder, a piston head having a bore extending axially therethrough, said bore being reduced at one end to define a valve seat interiorly of the bore, the other end of said bore being enlarged to define a piston-rod receiving-socket and a stop shoulder, one end portion of said head being of smaller diameter than the remainder of said head and adapted to define a space between said end portion and the cylinder in which the head is operated, a discharge port extending from the exterior of said reduced end portion and opening into said enlarged portion of said bore, a piston rod having an end portion mounted in said socket and abutting said shoulder, said end portion of said rod having an axial bore registering with the bore in said head, said end portion of said rod having a radial discharge port registering with the discharge port in said piston head and opening into the bore in said rod, a discharge check valve of smaller diameter than the bore in said head adapted to seat on said valve seat, a spring urging said discharge valve against its seat and extending into the bore in said rod, a spring keeper member mounted in

the bore in said rod, and a fastening pin extending through said head and rod disposed to hold the spring keeper member in place as well as to secure the piston rod and piston head together.

4. In a structure of the character described, a piston cylinder, a piston head having a bore extending axially therethrough, said bore being reduced at one end to define a valve seat interiorly of the bore, the other end of said bore being enlarged to define a piston-rod receiving-socket and a stop shoulder, one end portion of said head being of smaller diameter than the remainder of said head and adapted to define a space between said end portion and the cylinder in which the head is operated, a discharge port extending from the exterior of said reduced end portion and opening into said enlarged portion of said bore, a piston rod having an end portion mounted in said socket and abutting said shoulder, said end portion of said rod having an axial bore registering with the bore in said head, said end portion of said rod having a radial discharge port registering with the discharge port in said piston head and opening into the bore in said rod, a discharge check valve of smaller diameter than the bore in said head adapted to seat on said valve seat, a spring urging said discharge valve against its seat and extending into the bore in said rod, a spring keeper member mounted in the bore in said rod, and a fastening pin extending through said head and rod disposed to hold the spring keeper member in place as well as to secure the piston rod and piston head together, said keeper member being U-shaped and arranged to straddle said pin.

5. In a structure of the character described, a piston cylinder, a piston head having a bore extending axially therethrough, said bore being reduced at one end to define a valve seat interiorly of the bore, the other end of said bore being enlarged to define a piston-rod receiving-socket and a stop shoulder, one end portion of said head being of smaller diameter than the remainder of said head and adapted to define a space between said end portion and the cylinder in which the head is operated, a discharge port extending from the exterior of said reduced end portion and opening into said enlarged portion of said bore, a piston rod having an end portion mounted in said socket and abutting said shoulder, said end portion of said rod having an axial bore registering with the bore in said head, said end portion of said rod having a radial discharge port registering with the discharge port in said piston head and opening into the bore in said rod, a discharge check valve of smaller diameter than the bore in said head adapted to seat on said valve seat, a spring urging said discharge valve against its seat and extending into the bore in said rod, a discharge check valve of smaller diameter than the bore in said head adapted to seat on said valve seat, a spring urging said discharge valve against its seat and extending into the bore in said rod, a spring keeper member mounted in the bore in said rod, and a fastening pin extending through said head and rod disposed to hold the spring keeper member in place as well as to secure the piston rod and piston head together.

yieldingly holding the discharge valve seated, and a removable fastening element inserted through the reduced end portion of said piston head and said rod to hold the rod socketed in the head and said bores and said discharge ports in registration.

5 6. In a structure of the kind described, a piston cylinder, a piston head having a bore extending axially therethrough, said bore being reduced at one end to define a valve seat interiorly of the bore, the other end of said bore being enlarged to define a piston-rod receiving-socket and a stop shoulder, one end portion of said head being exteriorly cut away to define a space between said end portion and the cylinder in which the head is operated, said space extending to the inner end of said cut-away portion and opening into said enlarged portion of said bore, a piston rod having an end portion mounted in said socket and abutting said shoulder, said end portion of said rod having an axial bore registering with the bore in said head and being formed with a discharge port affording communication of said registering bores with the discharge port in said head, a spring loaded check valve assembly mounted on said bores and normally seating on said valve seat, and a fastening pin inserted through said head and rod for holding them together.

10 7. In a valved piston assembly, a cylinder, a piston head reciprocable in said cylinder and having a bore extending axially therethrough, said bore being reduced at one end to define a valve seat interiorly of the bore, the other end of said bore being enlarged to define a piston-rod receiving-socket and a stop shoulder, one end portion of said head being exteriorly cut away to define a space between said end portion and the cylinder in which the head is operated, said space extending to the inner end of said piston head, a discharge port leading from the exterior of said cut-away portion and opening into said enlarged portion of said bore, a piston rod having an end portion mounted in said socket and abutting said shoulder, said end portion of said rod having an axial bore registering with the bore in said head, said end portion of said rod having a radial discharge port registering with the discharge port in said piston head and opening into the bore in said rod, a discharge check valve of smaller diameter than the bore in said head adapted to seat on said valve seat, a spring urging said discharge valve against its seat and extending into the bore in said rod, a spring keeper member mounted in the bore in said rod, and a fastening pin extending through said head and rod disposed to hold the spring keeper member in place as well as to secure the piston rod and piston head together.
